UNITED STATES PATENT OFFICE.

JOHN M. TRAVIS, OF ST. LOUIS, MISSOURI.

DESIGN FOR A BEVERAGE-DISPENSING APPARATUS.

Application filed May 5, 1921. Serial No. 467,208. Term of patent 14 years.

To all whom it may concern:

Be it known that I, JOHN M. TRAVIS, a citizen of the United States, residing at St. Louis, State of Missouri, have invented a new, original, and ornamental Design for Beverage-Dispensing Apparatus, of which the following is a specification, reference being had to the accompanying drawing, forming a part hereof.

The figure is a perspective view of a beverage dispensing apparatus showing my new design.

I claim:

The ornamental design for a beverage dispensing apparatus, as shown.

JOHN M. TRAVIS.
